UNITED STATES PATENT OFFICE.

HARRY E. GIFFORD, OF ONSET, MASSACHUSETTS.

MOISTURE-CHAMBER FOR BLOTTER-BATHS.

SPECIFICATION forming part of Letters Patent No. 628,657, dated July 11, 1899.

Application filed March 14, 1899. Serial No. 709,069. (No model.)

To all whom it may concern:

Be it known that I, HARRY E. GIFFORD, a citizen of the United States, residing at Onset, in the county of Plymouth and State of Massachusetts, have invented certain new and useful Improvements in Moisture-Chambers for Blotter-Baths; and I do hereby declare that the following is a full, clear, and exact description of the same, reference being had to the annexed drawings, making a part of this specification, and to the letters of reference marked thereon.

The present invention has relation to devices for dampening with water suitable absorbent sheets to be used in furnishing moisture in the copying of letters in letter-books under pressure. It is well known that manuscript writing with pen and ink requires less moisture of the absorbent sheets to take a press-copy than would be required in type-writing. It is therefore the purpose of the present invention to provide a moisture-chamber of the construction hereinafter described having dampening-surfaces upon both its upper and lower sides, so that when absorbent sheets are placed above and upon the upper side of the chamber the sheets will have the proper degree of moisture for copying pen-writing by capillary attraction and the sheets when placed underneath the chamber will have the required moisture for press-copying by the action of gravitation.

It is a further purpose of the invention to provide a reversible moisture-chamber having upon its opposite sides two different degrees of dampening or moistening surfaces, also in providing a simple and effective chamber in its several details of construction, as will be hereinafter described and claimed.

Figure 1 of the drawings is a perspective view of my improved moisture-chamber, showing it in the usual box or receptacle with the cover or lid thereof shown as partly raised and the absorbent sheets placed above and below the chamber; Fig. 2, a longitudinal vertical section of the moisture-chamber on an enlarged scale; Fig. 3, an edge view thereof; Fig. 4, a perspective view of one end of the moisture-chamber, showing one of the metal fastening or locking strips in position previous to its being bent down in place.

In the accompanying drawings, A represents a box or receptacle, and B the cover or lid thereof, both of which are preferably constructed of sheet metal and may be of any preferred size and shape. This box or receptacle is adapted to receive my improved moisture-chamber, as indicated at C, said chamber containing a filling G in bulk or in sheets of a suitable absorbent material, such as felt, flannel, sponge, soft absorbent paper-pulp, or any substance that will properly absorb and hold water. This chamber is preferably constructed of sheet metal, and each side is capable of being brought into use for moistening or dampening the sheets to be used in letter-press copying. To attain this end, both the sides are perforated, the perforations *a* being much smaller than the perforations *b*, thereby providing for two different degrees of moistening or dampening surfaces to be used in taking copies of pen-writing or type-writing, as may be found necessary. In place of making the holes *b* larger than the holes *a* for giving a greater degree of moisture, the holes may be the same size, but of greater number, which would serve the same purpose, or any means may be resorted to that will provide the two sides with different degrees of moistening or dampening surfaces.

Where the moisture-chamber is not intended to be reversible, the perforations may be of the same size and number and used as shown in Fig. 1 of the drawings.

In the present instance the absorbent sheets to be used for taking letter-press copies, as indicated at D and E, are placed both above and below the moisture-chamber C, the sheets E below the chamber receiving more moisture than the sheets D above said chamber, the sheets above being used for pen and the sheets below for type writing copying, thereby providing for the two different degrees of moistening or dampening without increasing the size or number of holes.

In using the moisture-chamber the same is placed under a faucet or submerged in water or otherwise brought in contact therewith until all it will hold has been absorbed, after which the chamber is placed in the box or receptacle adapted to receive it. If type-writing copying is desired, the chamber having

its side with the greatest degree of moistening or dampening surface is brought uppermost and the absorbent sheets used in press-copying are laid upon the same and taken off 5 for use as required. When pen-and-ink writing is to be letter-press copied, which requires a less degree of moisture on the copying-sheets, the chamber is reversed and the side having the lesser degree of moistening 10 or dampening surface is brought uppermost and the sheets placed thereon, as in former case. The same effect may be obtained by placing the sheets used in letter-press copying both above and below the moisture-chamber, giving to the sheets different degrees of 15 moisture for use in copying type-writing or pen-and-ink writing at the same time. The letter-press sheets below the chamber may be renewing their moisture while the sheets 20 above are being used without regard to copying type-writing or pen-and-ink writing.

It will therefore be seen that I have provided a moisture-chamber that may be used upon either side separately or both together, 25 as circumstances require, the chamber having surfaces upon both its sides of the same or different degrees of moisture, whereby it is capable of use in the manner hereinbefore described. So far as these features of the invention are concerned it is immaterial in 30 what manner the moisture-chamber is constructed to hold the absorbent material in bulk or in sheets, as any chamber with a filling of absorbent material and having perforations at top and bottom to provide moistening or dampening surfaces upon both its sides would serve the purpose of my invention without reference to the details of construction.

40 In constructing the moisture-chamber I prefer in the present instance to take two sheets of perforated sheet metal of the desired size and shape and bend their edges at right angles to form the end flanges *c*. These flanges 45 form the two opposite edges of the moisture-chamber, and the edges of the perforated metal sheets at right angles to the flanges *c* are bent to form grooves *d*, with which engage the flanges *e* of locking-strips *F*. These 50 flanges *e* extend outward and at right angles to the body of the locking-strip *F*, and the extremities of the strips terminate in tongues

f, which are bent down against the flanges *c*, as shown in Figs. 3 and 4 of the drawings.

The above construction provides a chamber 55 that will securely hold the absorbent material, and the locking-strips hold the two sheets forming the top and bottom of the chamber together. The locking-strips may be of any suitable construction and one or 60 more may be used, and the perforated top and bottom of the chamber may be constructed of a single sheet of perforated metal, as found most desirable, and any change or 65 modification in the details of construction may be resorted to without departing from the principle of the invention.

The material from which the chamber is constructed may be of any suitable rigid material in contradistinction to cloth, paper, or 70 other like soft material, sheet metal being the material most preferable.

Having now fully described my invention, what I claim as new, and desire to secure by Letters Patent, is—

75 1. A moisture-chamber constructed of sheet metal or other like rigid material and containing a filling of absorbent material and having upon its opposite sides two different degrees of dampening or moistening surfaces, 80 substantially as and for the purpose specified.

2. A reversible moisture - chamber constructed of sheet metal or other like rigid material and having perforations upon both its sides substantially as described whereby two different degrees of moistening or dampening surfaces are provided, substantially as and for the purpose described.

3. A moisture-chamber containing a filling 90 of absorbent material and having one or more of its edges bent to form grooves, and a flanged locking-strip engaging therewith and having tongues at its ends to bend down against the edges of the chamber to hold the 95 strips in place, substantially as and for the purpose specified.

In testimony that I claim the above I have hereunto subscribed my name in the presence of two witnesses.

HARRY E. GIFFORD.
